DRILL BIT WRENCH

George H. Coplen, Cripple Creek, Colo.

Application April 5, 1940, Serial No. 327,977

5 Claims. (Cl. 81—55)

Certain types of rock drills have removable bit heads which are threaded into the drill shank by means of a left handed thread. It is exceedingly difficult to remove these heads due to the fact that their particular shape is not adaptable to any of the standard wrenches and due to the fact that it is difficult to hold the drill shank while the head is being removed.

The principal object of this invention is to provide a unitary wrench which will simultaneously rotate the bit head and the drill shank in opposite directions to quickly and easily loosen and remove the bit therefrom.

Another object of the invention is to so construct the wrench that it can be placed directly onto the drilling extremity of the drill steel and need not be passed over the entire length of the steel.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a perspective view illustrating the improved tool in use on the extremity of a drill shank.

Fig. 2 is an inside face view of the tool.

Fig. 3 is a vertical section therethrough, taken on the line 3—3, Fig. 2.

Fig. 4 is a detail sectional view, illustrating the type of removable bit head for which the invention is designed.

In the drawing a typical drill shank is indicated at 29 and the detachable head thereof at 30. The invention employs a hollow, cylindrical socket 10 from which a handle 11 projects. The interior of the socket 10 is conformed by means of projecting bosses 25 to fit into the grooves of the usual drill bit head.

An outer sleeve member 12 surrounds the socket 10 and rests in a shouldered recess 13 therein. The sleeve member 12 may be held in place on the socket in any desired manner. As illustrated, it is held in place by means of an annular plate 14 secured thereto by means of suitable screws 15.

A hinge lug 16 projects from the face of the sleeve 12 and hinged supports a gripping member 17 upon a suitable hinge pin 18. The mem-

ber 17 is formed with relatively sharp ratchet teeth 19. Diametrically opposite from the lug 16 is an ear 20 which is drilled and tapped to receive a handle pivot bolt 21 upon which a second handle member 22 is hinged.

The second handle member is spaced from the annular plate 14 by means of suitable spacing washers 23. The handle member 22 extends inwardly beyond the pivot bolt 21 and terminates in an inclined extremity provided with sharpened ratchet teeth 24.

The outer face of the socket 10 is closed by means of a stop plate 26 which is slotted as shown at 27 in the shape of a cross to receive the crossed, sharpened edges of the drill bit head. The stop plate is held in place by means of suitable attachment screws 28.

In use, the open face of the tool is slipped over the drill bit head so that the grooves in the latter will receive the bosses 25 of the socket 10 and so that the edges of the bit head will project through the crossed slot 27, as shown in Fig. 3.

The gripping member 17 is swung against the shank and the handles 11 and 12 are taken in each hand and turned in opposite directions. This causes the teeth 19 and 24 to bite into the shank and rotate it in one direction while the socket member, through the medium of the lugs 25 and the slotted plate 26, grips the head and rotates it in the opposite direction, so as to readily unscrew the head from the shank.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A wrench for removing a drill bit head from a drill shank comprising: a socket member conformed on its interior to receive a drill bit head; a rotatable sleeve about said socket member; a handle fixed to and projecting from said socket member; a second handle pivoted on said sleeve; an inwardly projecting extremity on said second handle; teeth on said latter extremity for engaging a drill bit shank; and means for preventing said head from passing entirely through said socket member.

2. A wrench for removing a drill bit head from a drill shank comprising: a socket member conformed on its interior to receive a drill bit head; a rotatable sleeve about said socket member; a

handle fixed to and projecting from said socket member; a second handle pivoted on said sleeve; an inwardly projecting extremity on said second handle; teeth on said latter extremity for engaging a drill bit shank; means on said sleeve opposite said second handle for engaging a drill bit shank and a plate closing one face of said socket member to prevent said head from passing entirely therethrough.

3. A wrench for removing a drill bit head from a drill shank comprising: a socket member conformed on its interior to receive a drill bit head; a rotatable sleeve about said socket member; a handle fixed to and projecting from said socket member; a second handle pivoted on said sleeve; an inwardly projecting extremity on said second handle; teeth on said latter extremity for engaging a drill bit shank; and a transversely hinged, toothed, gripping member on said sleeve opposite from said second handle member to swing in a plane parallel to the axis of said socket member for gripping the opposite side of the drill bit shank.

4. A wrench for removing a drill bit head from a drill shank comprising: a hollow cylindrical socket member; projections on the interior of said socket member for engaging the grooved head of a drill bit; a handle fixedly projecting from said socket member; a head plate closing the first face of said socket member to hold a bit head in place therein; a cylindrical sleeve rotatably surrounding the socket member adjacent the second face thereof; a retaining ring about said second face for holding said rotatable

5 sleeve in place thereon; a pivot member projecting forwardly from said second face; a second handle member freely pivoted on said pivot member so as to swing in parallel relation with and in front of said second face; and teeth on one extremity of said second handle member for engaging the shank of a bit when the latter's head is in said socket member.

10 5. A wrench for removing a drill bit head from a drill shank comprising: a hollow cylindrical socket member; projections on the interior of said socket member for engaging the grooved head of a drill bit; a handle fixedly projecting from said socket member; a head plate closing 15 the first face of said socket member to hold a bit head in place therein; a cylindrical sleeve rotatably surrounding the socket member adjacent the second face thereof; a retaining ring about said second face for holding said rotatable 20 sleeve in place thereon; a pivot member projecting forwardly from said second face; a second handle member freely pivoted on said pivot member so as to swing in parallel relation with and in front of said second face; teeth on one extremity of said second handle member for engaging the shank of a bit when the latter's head is in said socket member; a hinge lug projecting forwardly from said cylindrical sleeve opposite said pivot member; and a toothed gripping member hinged on said hinge lug so that it may swing 25 in a plane parallel to the axis of said socket member against the bit shank.

GEORGE H. COPLEN.
